[57] **CLAIM**

The ornamental design for a bottle holding device, as shown and described.

DESCRIPTION

FIG. 1 is an isometric view of the present invention, taken from a location forwardly, above and off to one side of the bottle holding device of the present invention;

FIG. 2 is a side view thereof;

FIG. 3 is a front elevational view thereof;

FIG. 4 is a side view thereof, with the opposite side of that taken in FIG. 2;

FIG. 5 is a rear view thereof;

FIG. 6 is a top view thereof; and,

FIG. 7 is a bottom view thereof.

The broken line showing of a wine bottle is for illustrative purposes only and forms no part of the claimed design.
